UNITED STATES PATENT OFFICE.

EDGAR KIDWELL, OF PHILADELPHIA, PENNSYLVANIA.

STEAM-BOILER.

1,348,179.

Specification of Letters Patent. Patented Aug. 3, 1920.

Application filed March 4, 1919. Serial No. 280,581.

To all whom it may concern:

Be it known that I, EDGAR KIDWELL, a citizen of the United States, and resident of the city and county of Philadelphia and State of Pennsylvania, have invented certain new and useful Improvements in Steam-Boilers, of which the following is a specification.

This invention relates to steam boilers; having reference, more particularly, to that type of boilers wherein transverse receptacles and associated banks of water-tubes, together with suitable baffling, are employed, and wherein at least two of said receptacles are arranged partly above and partly below the normal level of the boiler water in order to constitute steam-and-water receptacles, whereof the respective steam-spaces are connected directly or indirectly by suitably-disposed drying or superheating tubes adapted to conduct the steam, which is liberated from the water in one receptacle, to the steam-space of the other receptacle preparatory to the discharge of the steam for service.

The object of my invention is to provide a simple and efficient construction whereby the true level of the boiler water within the steam discharge receptacle is correctly indicated, irrespective of the fluctuations of the water-level in the steam disengaging receptacle or other remote portion of the boiler, or the rate at which the boiler is being operated; thus effectually obviating the otherwise liability of the rising and mixing of the water with the steam, as the latter rushes into and is withdrawn from the discharge receptacle; and also enabling the proper and normal level of the boiler water to be easily maintained by the operator.

According to my invention I provide, in addition to the main water circulating path, of the boiler in which the steam-disengaging receptacle is included, a supplemental water circulating path in which the said receptacle and the steam discharge receptacle are included, said supplemental path being so disposed and proportioned in relation to the main path that the normal water-level within the discharge receptacle is maintained. I connect the water-gage glass directly to the water-space of the said discharge receptacle, and thereby secure an accurate indication of the normal level of the water in the boiler at all times.

The preferred construction herein illustrated embodying the principle of my invention will be hereinafter described and the scope of the invention then be defined in the appended claims.

In the drawings—

Figure 1 is a partial longitudinal vertical section of a boiler of the transverse drum type embodying my invention.

Fig. 2 is a vertical section of the apparatus as on the line 2—2 of Fig. 1.

Fig. 3 is a similar section, as on the line 3—3 of Fig. 1.

Fig. 4 is a section similar to Fig. 1, showing the boiler equipped with an additional steam-and-water drum and connections therefor.

Referring to the drawings, 10 designates the boiler setting; 11 the furnace therein, and 12 the outlet or breeching to the smoke-stack at the rear of the setting.

13 designates a mud drum at the rear of the bridge wall of the furnace; 14 a water drum located above the forward portion of the furnace and below the normal water-level, and 15, 16 two steam-and-water drums arranged above the drums 13, 14 respectively. The drums 15, 16 are located partly above and partly below the normal water-level, thus providing in each a lower water-space 17 and an upper steam-space 18. The feed-water pipe 19 leads into the rear drum 15. The drums 13, 14 and 15 are connected in succeeding order by banks of tubes 20, 21, 22 respectively, thus providing a continuous circulation path for the water; and baffles 23 are suitably-disposed in relation to such banks in order to direct the hot gases and other products of combustion through appropriate passes from the front to the rear of the apparatus, whereby a continuous circulation of the water through the drums and tubes is effected.

The steam-space of the rear upper drum 15 is connected with the similar space of the forward upper drum 16 by means of a series of tubes 24 which are preferably arranged within the path of the hot gases from the furnace, whereby the steam as rapidly as it is liberated from the water in the drum 15 flows into the steam-space of the forward upper drum 16, such steam, during its passage through the tubes, being effectually dried or superheated. The drum 15 is provided with a discharge portion 25

through which the dry or superheated steam as rapidly as it is produced is taken off for service.

The steam as it is disengaged from the water in the drum 16 causes a constant and substantial fluctuation of the normal water-level within said drum, thus rendering it difficult by the usual water-gage connection to determine with any degree of accuracy the level of the boiler water. Moreover, in some cases entrained water in the steam is liable to pass over to the forward drum through the tubes 24, and unless such water be withdrawn it floods the drum 16, and, perforce, commingles with and is carried off by the steam; thus negativing the function of the drying or superheating tubes.

In order to maintain a water-level within the drum 16 corresponding to the normal water-level within the steam-disengaging drum 15, irrespective of the disturbance of the water within the latter and of the delivery to the drum 16 of water carried over by the steam, I reduce the capacity of the tube bank 21 connecting the water drum with the steam-disengaging drum, and divert the proportion of water which otherwise would pass through said tubes, into a secondary path of circulation in which the drums 15, 16 are included; that is to say, I connect the drums 14 and 16 by means of tubes 26, and the drums 16 and 15 by means of a corresponding number of tubes 27, the capacity of which tubes 26, 27 is approximately equal to that of the tubes omitted from the bank 21. Thus a relatively small percentage of the water is diverted from the main circulation into the drum 16, and thence circulated to the drum 15 and back again to the main circulation, that is to say; the kinetic energy of the rising water in the drum 14 compels a flow through the tube connection 26 up to the forward steam-and-water drum, and the water-tube connection 27 enables the water to flow backward from the latter drum and thus complete the circulation. The tubes 27 are arranged within the path of the hot gases flowing from the furnace, and are upwardly inclined as shown from the front to the rear of the apparatus, in order to insure the circulation of the water from the water-space of the front to that of the rear steam-and-water drum.

It is to be noted that the volume of water diverted to and flowing through the secondary path is small compared with that flowing through the main path, the proportion being such that a steady level of the water within the drum 16, corresponding with the normal level of the water in the drum 15, is maintained irrespective of the disturbance of the water in the latter as above mentioned. I have found that with the relative area of the main passage, as

through the tubes 20, and the supplementary passage, as through the tubes 26, in the ratio of about 20 to 1, or 5 per cent. excellent results are attained, although, of course, I do not limit myself to that particular ratio or percentage. I attach the pipe connections 28 of the water-gage glass 29 directly to the drum 16, and hence the true level of the water within the boiler is accurately indicated irrespective of the agitation of the water in the steam-disengaging drum or other remote portion of the boiler.

In a boiler of narrow width I preferably arrange the auxiliary circulation tubes 26, 27 adjacent each side of the wall of the setting, as seen in Figs. 2 and 3, but in a wide boiler employing a larger number of main circulation water tubes, and therefore an increased number of auxiliary circulation tubes, I prefer to arrange the sets of auxiliary tubes at suitable intervals apart throughout the width of the boiler.

In order to prevent the steam from impinging against and disturbing the surface of the water contained within the drum 16, as the steam rushes into the latter from the drying or superheating tubes, I provide said drum with a horizontal deflecting plate 30 directly below the exit ends of such tubes and above the water-level, which plate diverts the steam from its downward path preparatory to escaping through the discharge portion 25. This plate is hinged to the inner side of the drum 16, as at 31, and is supported in horizontal position by hooks 32 which are positioned within the drum to engage eyes 33 on the plate. The plate is hinged and temporarily supported as just described in order that it can be readily unhooked and swung downward to facilitate access to the ends of the tubes 21, 22 when it is necessary to expand them into the tube holes in the wall of the discharge drum.

In case the feed-water supplied by the pipe 19 contains a large saline content, violent and constant foaming of the water within the drum 15 will occur and large bubbles be thrown off from the disengaging surface and carried over with the steam, thereby reducing the practical efficiency of the boiler. To overcome this objection in a boiler embodying the principle of my invention, I provide the construction illustrated in Fig. 4 of the drawings; that is to say, I equip the boiler with an additional steam-and-water drum 34 which is positioned at the rear of the apparatus and above and below the water-level; the steam-and-water spaces of such drum being connected with the corresponding spaces of the drum 15 by means of steam and water tubes 35, 36 respectively; the water-space of said drum 34 being connected with the mud drum 13 by a bank of tubes 37; suitable baffling

38 being arranged between such bank and the adjacent bank 22; and the feed-water supply pipe 19 leading into the additional drum instead of into the drum 15. The 5 drying or superheating tubes 24 lead from the steam-space of the drum 34 to the steam-space of the discharge drum.

In a boiler embodying the construction just described the feed-water enters the 10 drum 34; then slowly passes through and is preheated in the tube bank 37, thus precipitating many of the impurities contained in the water; then enters the mud drum 13 and passes into the main circulation. The 15 connection 36 tends to maintain a parity of water-levels in the drums 34 and 15, and therefore such connection is preferably used; but if desired it may be omitted. The wet steam from the drum 15 passes through 20 tubes 35 and enters the drum 34 at an angle to the axis of the latter, the entrained water, by reason of its momentum, being projected down upon and commingling with the relatively quiescent water in said drum 35. 25 Such steam then passes into and through the tubes 24 wherein it is dried and superheated before entering and flowing from the discharge drum 16.

It is to be understood that the particular 30 design of the boiler below the water-level does not affect the principle of my invention as applied thereto; and therefore I do not limit myself to the specific type or design of boiler herein selected to exemplify my invention. It is also to be understood that I 35 do not restrict myself to the details of construction herein disclosed, such, for example, as the number and form of the tubes in the main and supplemental paths of circulation, 40 as such features may be varied in many respects within the spirit of the invention and the scope of the appended claims.

I claim—

1. A steam-boiler having a continuous 45 main water circulation path and a supplemental water circulation path, said main path including a steam-and-water receptacle wherein the steam is disengaged from the water, and said supplemental path comprising 50 a steam-and-water receptacle from which the steam is discharged from the boiler, said latter receptacle being outside the main path of circulation, means whereby a relatively small portion of water is diverted from the main path of circulation and caused to flow into the discharge receptacle, and means located within the heating zone of the furnace whereby a corresponding flow of water from the discharge receptacle back to the main path of circulation is effected, and means for conducting the steam from the steam disengaging receptacle to the steam discharge receptacle.

2. A steam-boiler having a continuous 55 main water circulation path and a supple-

mental water circulation path communicating with the front and rear portions respectively of the main path, said main path including at its rearward portion a steam-and-water receptacle wherein the steam is 70 disengaged from the water, and said supplemental path comprising at its forward portion a steam-and-water receptacle from which the steam is discharged from the boiler, said latter receptacle being outside 75 the main path of circulation, means whereby a relatively small portion of the main body of circulating water is diverted into the discharge receptacle, and means located within the heating zone of the furnace whereby a 80 flow of water from the front to the rear steam-and-water receptacle is effected, and means for conducting the steam from the rear to the forward receptacle.

3. A steam-boiler having a continuous 85 main water circulation path and a supplemental water circulation path communicating with the front and rear portions respectively of the main path, said main path including at its rearward portion a steam-and-water receptacle wherein the steam is 90 disengaged from the water, and said supplemental path comprising at its forward portion a steam-and-water receptacle from which the steam is discharged from the 95 boiler, said latter receptacle being outside the main path of circulation, means whereby a relatively small portion of the main body of circulating water is diverted into the discharge receptacle, and means located 100 within the heating zone of the furnace whereby a flow of water from the front to the rear steam-and-water receptacle is effected, and means for conducting the steam from the rear to the forward receptacle, and 105 a water-gage directly connected to the front receptacle.

4. A water-tube boiler having front and rear transverse steam-and-water drums, a forward water drum, a rearward mud drum, 110 a bank of tubes connecting said mud drum to the water drum, a second bank of tubes connecting said water drum to the rear steam-and-water drum, a third bank of tubes connecting said rear drum to the mud 115 drum, a relatively small water tube connection between the water drum and the water-space of the front steam-and-water drum, a relatively small tube connection between said water-space and the water-space of the 120 rear steam-and-water drum, said latter tube connection being located within the heating zone of the furnace, and means for conducting the steam from the rear to the front steam-and-water drum.

5. A water-tube boiler having front and rear transverse steam-and-water drums, a forward water drum, a rearward mud drum, 125 a bank of tubes connecting said mud drum to the water drum, a second bank of tubes 130

connecting said water drum to the rear steam-and-water drum, a third bank of tubes connecting said rear drum to the mud drum, a relatively small water tube connection between the water drum and the water-space of the front steam-and-water drum, a relatively small tube connection between said water-space and the water-space of the rear steam-and-water drum, said latter tube connection being located within the heating

zone of the furnace, and means for conducting the steam from the rear to the front steam-and-water drum, together with a water-gage directly connected to the front steam-and-water drum.

15

Signed at New York in the county of and State of New York this third day of March A. D. 1919.

EDGAR KIDWELL.
